PNEUMATIC LIFE BELT

James D. Garvey, Chicago, Ill.

Application December 24, 1932, Serial No. 648,788

3 Claims. (Cl. 9—17)

My invention relates to a pneumatic type of life belt and especially to a type involving separately inflatable sections or members, with each section or member of a capacity adapted to induce flotation of the user or to at least cause the body of the user to come to the surface of the water, in the event that all sections or members are not inflated, or the various members or sections are only partially inflated.

10 The object of my invention is to provide a life belt which may be applied to the body before the belt is inflated and which will be so secured that it not only will remain in proper position, but will also be so arranged that the user may easily and quickly inflate the respective sections.

15 In the event that it is found that the degree of inflation is not ample to induce desired flotation, the user may readily inflate to a further degree and thus ensure the desired condition; the belt being adjustable, within given dimensions, to varying sized bodies.

Another object of the invention is to so secure the inflatable sections or members that they will remain in place; and injury to one section or member will not destroy the usefulness of the belt.

These objects and advantages, as well as other advantages inherent in the construction, will 30 all be readily comprehended from the following detailed description of the accompanying drawings, wherein:—

Figure 1 is a perspective view of my improved life belt in inflated condition.

35 Figure 2 is a cross sectional view taken for example on the line 2—2 of Figure 1.

Figure 3 is a sectional elevation through the belt at one end of the inflatable member immediately adjacent and fastened to the belt.

40 Figure 4 is a top plan of a portion of the inflated belt.

Figure 5 is an enlarged sectional view of the two ends of the smaller or inner member and means for reducing its circumferential length.

45 Figure 6 is a detail sectional view of the air valve and portion of one of the air tubes.

Figure 7 is an end view of the valve.

My improved life belt, as disclosed in the drawings, involves a belt 15 of suitable pliable material, which is intended to be secured about the waist of the wearer; with the ends of the belt adjustably fastened by any suitable means or buckle as shown at 16. This belt is preferably of length to enable its use by different sized individuals, within given range. The belt 15

is provided with a pair of shoulder straps 17, 17, preferably arranged to cross each other at least at the back at a distance from the points of attachment to the belt so as to prevent these straps 17, 17 from slipping off the user's shoulders.

Disposed immediately adjacent to the belt 15 is an inflatable elongated tube 18 of suitable length and provided with an inflating tube 19, whose outer end is provided with a suitable mouth-piece 20.

The mouth-piece is preferably of the oval shape shown so as to be easily taken into the mouth for inflating purposes. The mouth-piece consists of a member 21 fixedly secured in any suitable air-tight manner to the end of the tube and the opposite end of the member 21 reduced in diameter and externally threaded to receive the inner threaded end of the other member 22, so as to provide a smooth outer surface, see Figure 6.

This shell member 22 is open at its outer end, with the opening surrounded by the inwardly disposed annular flange 23.

Shell member 22 constitutes a housing for the valve which, in the particular exemplification, consists of the annular disc 24, which is shown dished and held against the flange 23 by a suitable coil spring 25, seated at one end in the dished side of the valve-disc, while the other end of the spring seats on the shoulder formed by the reduced end of the member 21. As is apparent, the valve-disc is firmly held on its seat and hence will prevent egress of air from the tube; while on the other hand it may be readily dislodged from its seat by blowing into the end of member 22 when the mouth-piece has been taken into the mouth.

The belt is shown provided with three inflated elongated tubes 18, 26 and 27, each of somewhat greater length so as to enable the tubes to be concentrically arranged when inflated, as shown in Figures 1 and 2; the length of the tubes 26 and 27 being such that the ends of each tube will be in close proximity to each other. These tubes are, of course, made of thin rubber, with the ends closed and sealed in any well known manner, against egress of air.

The tubes 26 and 27, like tube 18, are also each provided with an inflating tube 28 and 29, respectively, and their outer ends each provided with a similar valve holding mouth-piece 20, as shown in Figure 1.

The inflating valved tubes 19, 28 and 29 are of length sufficient to have the mouth-piece 55

valves in close proximity to the mouth of the user; and in order that they may at all times be within convenient reach and position, I provide one of the shoulder straps, namely strap 17, near its top on the portion which will be disposed close to the user's chin, with a loop as at 17^a, through which the inflating tubes 19, 28 and 29 are passed and held in position as shown in Figure 1, where the valved mouth-pieces 20 are constantly in position to be quickly taken into the mouth for inflation or further inflation should it be necessary, while the user is in the water.

The air holding tubes 18, 26 and 27 are each provided with loops formed integral with each tube. These loops may be formed by strips 30 of rubber vulcanized or formed integral with the tubes; the strips at spaced intervals being left uncemented so as to provide loops or passageways for the straps whereby they are secured to the belt 15. That is to say, the tube 18 is secured by a series of straps 31 at spaced intervals about the belt; tube 26 is secured in place to the belt 15 by the straps 32; while the tube 27 is secured to the belt 15 by the straps 33; the straps being secured in any suitable manner to the belt proper 15; the ends of the straps being secured together by snap fasteners.

Each tube is therefore separately secured to the belt so as to be readily removed and replaced should occasion require.

In order to permit easy adjustment of the belt 15 so as to fit different sized waist lines and also permit ready access to the buckle 16, I show the tube 18, at one end, provided with a take-up member 34, see Figure 5. This member 34 is shown in the nature of an annular cup-shaped disc provided with an opening at 35 which is preferably surrounded by curved walls as at 36 so as not to present a sharp edge to the rubber tube which is passed through the hole 35.

This member 34 is also provided with eyeleted openings as at 37 (see Figure 3) to receive the cord or lacing 38 as shown in Figure 3. Where the life belt is worn by an individual having a waist-line smaller than the maximum length of the tube 18 would provide, one end of the tube, as at 18^a, is passed through hole 35 and folded up against the member 34 and this folded end held in place by the lacing 38 as shown; this folding of the tube-end being done, of course, before the tube is inflated; thereby reducing the circumferential size of the inflated portion of the tube.

When the maximum size of the tube is desired, the lacing 38 may readily be unlaced, the end 18^a of the tube released and member 34 removed.

The tubes, when not in use, may be quickly deflated by unseating the valves 24, which are shown provided with the small stems or pins as at 39 in Figure 6.

My improved lift belt is especially intended for use by swimmers and therefore has been devised to enable rapid inflation while in the water when the swimmer fatigues or becomes incapacitated by cramps or otherwise being primarily intended for use during emergency and hence may be left deflated so as not to interfere while swimming.

I have shown the belt provided with separate and independent inflatable sections or tubes,

so that the sustaining capacity is not only thereby increased, but in the event of an injury to one section or tube, the belt will not become useless but will still enable the user to obtain a floating or sustaining condition.

By having each section or tube independent of the belt proper and at the same time securely fastened to the belt, the belt may be more firmly secured about the body to ensure its proper positioning; a condition essential to its effectiveness; this positioning being further ensured by the shoulder-straps shown.

The exemplification of the invention is believed to be the best embodiment thereof and has been described in terms merely employed for purposes of description; it being understood, however, that modifications may be made without departing from the spirit of my invention.

What I claim is:

1. A life belt comprising an adjustable belt adapted to fit about the waist of the user; an elongated inflatable tube disposed about said belt and provided with an inflating tube; means for reducing the length of said inflatable tube in keeping with the adjustment of said belt consisting of a disc provided with an opening having a beaded perimeter for passage of the end of said tube therethrough before inflation and lacing secured to said disc adapted to receive the folded non-inflated end of the tube therebeneath; and means whereby said tube is secured to said belt.

2. A life belt comprising an adjustable belt adapted to fit about the waist of the user and provided with shoulder-straps; an elongated inflatable tube disposed about the belt and provided with a series of loops formed integral therewith and having a long upwardly extending inflating tube provided at its upper end with a valved mouth-piece; a plurality of tape secured to the belt adapted to pass through said loops for removably securing the inflatable tube in place; means on the shoulder-straps for holding the mouth-piece in proximity to the mouth of the user; and means for reducing the length of the inflatable tube in keeping with the adjustment of the belt consisting of a disc having an opening adapted to receive the non-inflated end of the inflatable tube, the disc between said opening and its perimeter having series of holes provided with a lacing whereby the folded end of the tube may be held against the disc.

3. A lift belt comprising an adjustable belt adapted to fit about the waist of the user; an elongated inflatable tube disposed about the belt and provided with an inflating tube; means for reducing the length of said inflatable tube consisting of a rigid member provided with an opening therethrough adapted to permit one end of the inflatable tube to pass through said opening before inflation, said member having a plurality of eyelets between the opening and its perimeter provided with lacing threaded therethrough whereby the non-inflated portion of the tube disposed through the opening in the member will be held against the side of the member beneath the lacing, and means whereby the inflatable tube is removably secured to said adjustable belt.

JAMES D. GARVEY.
